Attorney

UNITED STATES PATENT OFFICE.

AUGUSTUS A. MARTUS, OF BROWN CITY, MICHIGAN.

BEAN-ASSORTING MACHINE.

1,298,988.

Specification of Letters Patent.

Patented Apr. 1, 1919.

Application filed June 12, 1918. Serial No. 239,628.

To all whom it may concern:

Be it known that I, AUGUSTUS A. MARTUS, a citizen of the United States, residing at Brown City, in the county of Sanilac and State of Michigan, have invented certain new and useful Improvements in Bean-Assorting Machines, of which the following is a specification, reference being had to the accompanying drawings.

This invention relates to certain improvements in bean assorting machines and it is an object of the invention to provide a device of this general character having novel and improved means whereby the bad or cull beans may be readily separated.

It is also an object of the invention to provide a device of this general character including a hopper discharging upon an endless carrier and wherein said carrier comprises a plurality of flexible strands through which the bad or cull beans may be readily forced therebetween by a slight pressure thereon.

The invention also has for an object to provide a novel and improved device of this general character including a hopper discharging upon an endless separating member together with means for controlling the discharge of the beans upon the member.

The invention consists in the details of construction and in the combination and arrangement of the several parts of my improved bean assorting machine whereby certain important advantages are attained and the device rendered simpler, less expensive and otherwise more convenient and advantageous for use as will be hereinafter more fully set forth.

The novel features of my invention will hereinafter be definitely claimed.

In order that my invention may be the better understood I will now proceed to describe the same with reference to the accompanying drawings, wherein:

Figure 1 is a view in side elevation of a bean assorting machine constructed in accordance with an embodiment of my invention;

Fig. 2 is a view in front elevation of the device as herein disclosed;

Fig. 3 is a vertical longitudinal sectional view of the device as herein embodied;

Fig. 4 is a sectional view taken substantially on the line 4-4 of Fig. 3;

Fig. 5 is an enlarged fragmentary view, 55 partly in elevation and partly in section of the assorting member as herein employed;

Fig. 6 is a fragmentary view in top plan of the assorting member as disclosed in Fig. 5; and 60

Fig. 7 is an enlarged fragmentary detail illustrating the mounting of the valve co-acting with the hopper.

As disclosed in the accompanying drawings H denotes a hopper supported by two 65 sills 2 arranged substantially in horizontal alinement and in predetermined spaced relation. The sills 2 are supported at the desired elevation through the medium of the side frames 3. Coacting with the side 70 frames 3 are the horizontally disposed brace members 4. The hopper H comprises the end members 5, the side members 6 and the downwardly and inwardly inclined bottom member 7 which terminates inwardly 75 of the side member 6. The lower portion of the side member 6 is provided with the opening 8 through which the beans to be assorted are discharged. The end members 5 adjacent the side member 6 are provided 80 in their opposed faces with the inwardly and downwardly inclined grooves 9 in which are slidably engaged the end marginal portions of the valve 10 which is preferably maintained in various elevations by friction. 85

Supported by the end members 5 of the hopper H below the lower or forward marginal portion of the inclined bottom 7 is the rod 11 and pivotally engaged with the rod 11 is a chute 12 of a width to extend through the opening 8 in the side member 6 and the forward marginal portion of the chute 12 contacts by gravity with the periphery of the ratchet member 14 fixed to the shaft 15. The shaft 15 is rotatably 95 supported by the forwardly directed extension 16 carried by the hopper H. As the shaft 15 is rotated the ratchet member 14 carried thereby will vibrate the chute 12 whereby the discharge of the beans from said 100 chute is effected and which also results in an effective distribution of the beans so that the same will be received to best advantage by the separating member M to be hereinafter more particularly referred to.

The chute 12 is of a length substantially equal to the space between the end walls 5 of the hopper H and the end marginal por-

tions of said chute are provided with the upstanding flanges 17 whereby the beans delivered to the chute from the hopper H are prevented from obstructing or interfering 5 with the required vibration of the chute. As herein disclosed an end portion of the shaft 15 is provided with a pulley 18 around which is directed a belt 19 and the belt 19 is also directed around a pulley 20 fixed to 10 the shaft 21 disposed transversely of and rotatably supported by a rear portion of the frame F. The frame F has the hopper H resting directly upon the rear portion thereof and said frame F is secured to the sills 15 2 hereinbefore referred to. The shaft 21 adjacent the pulley 20 is provided with a balance wheel 22 and operatively connected with the balance wheel 22 is a pitman 23 which is also operatively engaged with a 20 treadle 24 supported by and positioned between the lower portions of the frame 3. While the shaft 21 is herein disclosed as being manually operated, I do not wish to be understood as limiting myself in this respect 25 as it is to be understood that this shaft may be rotated in any manner desired.

Fixed to the shaft 21 within the frame F and adjacent the sides of said frame are the sprocket wheels 25 and disposed over said 30 sprockets are the endless chains 26. The chains 26 also pass over the pulleys 27 carried by the shaft 28 disposed transversely of and supported by the forward end portion of the frame F. The chains then extend 35 downwardly and over the pulleys 29 carried by the shaft 28 rotatably supported by the side frames 3. By this arrangement, the upper stretches of the chain travel in substantially a horizontal path and in a direction 40 away from the hopper H.

Transversely alined links of chains 26 are connected by the rods 30 and encircling each of said rods is a coil spring 31 of an expandable type.

45 Overlying the rods 30 is a plurality of flexible strands 32 preferably cord and which are arranged in substantial parallelism. These strands 32 are threaded through the convolutions of the springs 31 and overlie the rods 30. The strands between adjacent rods may be readily forced apart by imposing slight pressure upon the beans supported between adjacent strands.

In practice the beans are discharged over 50 the chute 12 and as the same are carried forwardly it is only necessary for the operator to impose a slight pressure by a finger upon a bad or cull bean and the same will be forced between adjacent strands 32 and 55 thereby separated from the prime or good beans. Positioned between the stretches of the chains 26 is the collecting chamber C provided with the laterally directed discharge spout 33 through which the separated 60 culls or beans are delivered.

34 denotes the downwardly and rearwardly inclined chute disposed in a direction longitudinally of the frame F and the prime or good beans are delivered into the upper end thereof from the upper stretch of the 70 assorting member as afforded by the chains 26 and the elements carried thereby.

Also positioned between the stretches of the chains 26 is a hopper 35. This hopper 75 35 is also positioned directly below the discharge end of the chute 12 so that as the beans are delivered upon the strands 32, sand and other small matter will pass between the strands 32 and be collected within the hopper 35. The hopper 35 is provided 80 with the discharge chute 36 which extends downwardly on a predetermined incline and preferably in a direction away from the spout 33 hereinbefore referred to.

I also find it of advantage to arrange 85 within the hopper H above the valve 10 a stationary guide plate 37 delivering upon the inclined bottom 7. The guide plate 37 serves to relieve the valve 10 of the weight of the beans within the hopper H so that the 90 valve 10 may be manipulated with facility.

From the foregoing description, it is thought to be obvious that a bean assorting machine constructed in accordance with my invention is particularly well adapted for 95 use by reason of the convenience and facility with which it may be assembled and operated and it will also be obvious that my invention is susceptible of some change and modification without departing from the 100 principles and spirit thereof and for this reason I do not wish to be understood as limiting myself to the precise arrangement and formation of the several parts herein shown in carrying out my invention in practice except as hereinafter claimed.

I claim:

1. A device of the character described comprising an assorting member consisting of a pair of endless members, rods connecting said members, coil springs encircling the rods and interposed between the members, and flexible strands extending in the same general direction as the endless members and threaded through the convolutions of 115 the springs.

2. A device of the character described comprising an assorting member consisting of a pair of endless members, rods connecting said members, coil springs encircling the 120 rods and interposed between the members, and flexible strands extending in the same general direction as the endless members and threaded through the convolutions of the springs, said strands overlying the rods. 125

3. A device of the character described comprising an endless assorting member, a hopper discharging thereon, a chute into which the assorting member discharges, a collecting chamber positioned between the 130

stretches of the assorting member, and a second chute positioned between the stretches of the assorting member below the point upon which the first named hopper dis-
5 charges upon the upper stretch on the assort-
ing member.

In testimony whereof I hereunto affix my signature in the presence of two witnesses.

AUGUSTUS A. MARTUS.
